S. Goge,
Glove.

No. 91113.

Patented June 8, 1869

United States Patent Office.

SIGMOND GOGE, OF BROOKLYN, NEW YORK.

Letters Patent No. 91,113, dated June 8, 1869.

IMPROVEMENT IN GLOVES.

The Schedule referred to in these Letters Patent and making part of the same.

To all whom it may concern:

Be it known that I, SIGMOND GOGE, of Brooklyn, in the county of Kings, and State of New York, have invented and made a certain new and useful Improvement in Gloves; and I do hereby declare the following to be a full, clear, and exact description of the said invention, and of the features that distinguish the same from the gloves heretofore manufactured.

This invention is especially adapted to the manufacture of fur-gloves, but may be applied to other characters of gloves.

It has heretofore been usual to form gloves with the leather, or other material composing the palm, extending up, and also forming the inside surfaces of the fingers, and then between the fingers there have been separate pieces sewed in, there being two seams, one between the strip and the leather of the palm and fingers, and the other between the strip and the leather of the outside or back of the glove. These seams are liable to rip, particularly with heavy gloves, and under the movement of the fingers.

Fur-gloves have also been made with the palm-piece and first and fourth fingers of one piece of leather, and with the second and third-finger pieces united by a straight seam to the palm-piece; hence this straight seam comes at the point where the fingers bend, and is very objectionable, as the seam is pressed into the hand when any article is grasped. Besides this, the seam, running across the base of the second and third finger, stiffens the glove at this point, and interferes with the free movement of the hand in opening or closing the same.

The nature of my said invention consists in a glove in which the palm, the second and third-finger pieces are cut, so that the seams converge to a point toward the middle of the palm, thereby insuring a much better-fitting glove, and allowing greater freedom of movement to the hand, and the seams come between those portions of the palm of the hand on which pressure

usually comes; hence the seams do not injure the hand.

In the drawing—

Figure 1 represents a complete glove.

Figure 2 shows the palm-piece *a*, and first-finger piece *b*, and fourth-finger piece *c*, in the shape in which they are cut from a flat piece of material.

Figure 3 shows the piece of material for the thumb, the edges 1, 2, 3, of figs. 2 and 3, being sewed together to form the seam between the palm and thumb.

Figure 4 shows the second-finger piece. This is united at the edges 4, 5, and 6, with the corresponding edges of the piece, fig. 2.

Figure 5 shows the third-finger piece, that is united at the edges 6, 7, and 8, with the corresponding edges in fig. 4, and with the edges 6, 9, and 10 in fig. 2.

By reference to fig. 1, it will be seen that the seams thus formed converge to the point 6, in the palm-portion of the glove, near the point toward which the palm of the hand contracts in grasping an article; hence the seams do not interfere with the bending or contraction of the glove with the hand.

The material forming the back of the glove may be in one piece, cut out so as to be united to the edges of the leather or other material forming the inside of the glove.

What I claim, and desire to secure by Letters Patent, is—

The glove, formed with the seams of the second and third-finger pieces converging to the part 6 in the palm, substantially as and for the purposes set forth.

In witness whereof, I have hereunto set my signature, this 4th day of February, 1869.

SIGD. GOGE.
